[57] CLAIM

The ornamental design for the handle for a palm driver, as shown and described.

DESCRIPTION

FIG. 1 is a perspective view of the handle for a palm driver showing our new design;

FIG. 2 is a top plan view thereof;

FIG. 3 is a bottom plan view thereof;

FIG. 4 is an end elevational view of one end thereof; the other end being identical; and,

FIG. 5 is a side elevational view thereof, the other side being identical.

The broken line showing of the mechanism in FIGS. 1-5 is for illustrative purposes only and forms no part of the claimed design.
